UNITED STATES PATENT OFFICE

1,937,277

PRODUCTION CALCULATOR

Heinrich Kaffine, West Reading, Pa.

Application November 24, 1931
Serial No. 576,975

4 Claims. (Cl. 235—89)

The object of the invention is to provide broadly a production calculator, but more particularly one which is so designed as to calculate or estimate both the rate of feed and the speed of the tool 5 employed for a given operation in a milling machine.

It is well known by practical mechanics, by production managers of machine shops, and by tool designers that various factors enter into the operation of a tool in any form of cutting machine.

In now considering a milling machine, the important factors comprise the relative strength of the article to be milled, the relative strength of the tool, the particular kind of operation involved, the width and depth of the cut, the material of which the article is composed, the horsepower of the machine, and the diameter of the tool. All of these factors bear a definite relation to the speed at which the tool should progress 20 through the article being milled in order to obtain the most efficient results, and the rate of this speed is determined by, and is therefore subdivided into the feed, or the rate at which the article is fed past the cutter, and the surface speed of the 25 cutting tool, that is, the co-relation between the diameter of the cutting tool and its revolutions per minute. Therefore, an object is to provide a calculator having relatively movable parts bearing numerical factors, so arranged that by shifting 30 said parts as hereinafter described the information sought can be read directly therefrom.

With these and other objects in mind, the present invention comprises further details of construction and operation which are fully brought 35 out in the following description when read in conjunction with the accompanying drawing, in which Fig. 1 is a plan view of the obverse of a device comprising one embodiment of the invention; Fig. 2 is a similar view of the reverse of the 40 same; Fig. 3 is a plan view of the graduated slide per se (horizontally arranged); and Fig. 4 is a transverse section on the line 4—4 of Fig. 1.

Referring to the drawing, a member comprising 45 a card of stiff paper board or a plate of preferably light-weight material 1 is provided with a longitudinally extending channel 2 of either less than, or throughout, the entire length of said member, and through which a slide 3 is adapted to reciprocate. Said member adjacent to one end of said 50 channel may be cut away at 4, if desired, to make it easy to manually engage said slide when it is in its innermost position. Also, said member is provided upon its obverse face with apertures or 55 windows 5, 6, 7, 8 and 9, which in each instance extend through the wall of and into said channel,

so that indicia carried by said slide can be readily seen therethrough.

Referring now to the obverse surface of the calculator, upon one side of the first aperture 5 are two tables 10 and 11, side by side and containing 60 in the former table in vertical arrangement several terms, which are descriptive of the article to be milled, namely, "Fragile", "Medium" and "Strong", while in the latter table are several terms, which are descriptive of the holding or 65 clamping "Tool" to be employed in the operation, namely, "Light", "Medium" and "Strong". Upon the opposite side of the aperture 5 is a table in which are listed in vertical arrangement the several types of operations for which the milling machine is adapted, including "Sawing", "Vertical slotting", "Vertical milling", "Slotting", "Surface milling", "Side milling" and possibly others. 70

Below the first aperture 5 is the second aperture 6, to one side of which are tables 13 and 75 14 in which are listed, respectively, the width and depth of the cut to be made, while upon the opposite side of said second aperture is a table 15 in which are listed also in vertical arrangement the various metals of which the article to 80 be milled may be composed, namely, "Tool steel", "Drill rod", "Cold drawn steel", "Screw steel", "Cast iron", "Machine steel", "Cold rolled steel", "Brass" and "Aluminum".

Below the aperture 6 is the third aperture 7, 85 to one side of which are two tables in which are listed, respectively, the "Horsepower of the machine" and the "Diameter of the cutter". Still below said last-named aperture is the fourth aperture 8 through which one of the composite 90 factors is viewed as hereinafter described, while to the side of said last-named apertures 7 and 8 is the fifth and final aperture 9, to one side of which is a table 18 in which are vertically arranged the several types of metal also listed 95 in table 15, but in this instance for indicating the "Cutting speed" required for the particular metal (or other material being handled).

Referring now to the slide 3, its surface is 100 provided with two normally vertical rows 19 and 20 of figures, which are adapted to be shifted step by step and viewed and read in the first instance through the apertures 5, 6, 7 and 8 in sequence, and in the second instance through the aperture 9. The reverse of the plate member 1 is in 105 turn provided with a "Table of cutting speeds", comprising horizontal lines 21, opposite figures denoting the "Diameter in inches" of the milling tool and vertical columns 22 corresponding with the "Feet per minute" of the cutting speed. 110

Within the spaces in which said lines and columns intersect there are numerals to denote the "Revolutions per minute" at which the cutting tool is to be rotated.

5 The operation of the calculator is as follows:— Assuming that the part to be milled is of "Fragile" construction, reading to the right we find ".582". The slide 3 is then pulled down until ".582" is even with or abreast of the last 10 line 10' of the first table 10. If the supporting or positioning tool or clamp is of but medium strength, we find now opposite the word "Medium" the figure ".438", which in turn is brought down (by further moving the slide 3) until said 15 figure is opposite the last line 11' of said second table. If the work to be done is a surface milling operation, the figure ".364" now opposite the term "Surface milling" in table 12 is brought down (by further moving the slide 3) until said 20 last-named figure is opposite the last line 12' in the "Operation" table.

If the width of the desired cut is under $\frac{1}{8}$ ", the figure "2.175" now opposite that line in table 13 is brought down to the last line 13' in 25 said table. If the depth of the cut is " $\frac{1}{8}$ "—1", the figure "1.125" now opposite that indication in table 14 is brought down until it is opposite the last line 14' in that table. If the material is of cast iron, the figure ".640" is brought into 30 alignment with the last line 15' in the table 15 of materials. If the horsepower of the machine is "1-3", the figure "1.492" now opposite that power indication is brought down to the last line 16' in the table 16, and if the diameter 35 of the cutter is "1-2" inches, the figure "1.358" is lowered into alignment with the last line 17' of the table 17.

The necessary, or at least the advisable, rate of feed of the movable bed of the milling machine, having been automatically brought into unobstructed view, can now be read through the "Feed" aperture 8, and in this case will be seen to be "1.802" feet per minute, so that the "feed" of the machine may be readily set in the usual manner at the point or rate nearest to that figure which the construction of the particular machine permits. For the revolutions per minute at which the tool should be run, we first look through the aperture 9 and opposite the designation "Cast iron" find the figure "86.6", the correct cutting speed in feet per minute of the cutter. Turning the calculator over, we find upon the reverse side in the uppermost horizontal column that "90" is the figure nearest to the "86.6". In the farthest left hand (or farthest right hand) vertical column we look for the diameter of the cutting tool being used, which in this instance may be $1\frac{1}{8}$ ". Reading horizontally across from this figure, and vertically below the "90", we find 60 "183" which is substantially the exact number of revolutions per minute at which the tool in this case should theoretically be run. (All of the figures of this table are not filled in.) Obviously, if there is no means upon the particular machine 65 for setting the speed at the exact figure designated by the table, the speed should be set as near as possible to that figure.

In making use of the improved calculator, it should be borne in mind that it is primarily intended for use with milling work with high-speed steel cutters, and when the average fairly clean finished surface is desired after only a single cut, as is usually the case in mass production. In case carbon steel cutters are being used, only one- 75 half the estimated feed and speed should be used.

At times it is also advisable to make two cuts, in order to leave a much smoother finished surface than is usually possible with but a single cut, or whenever greater accuracy is demanded. In such cases one makes a roughing cut to remove the bulk of the material, and leaves only sufficient material to provide for a relatively thin finishing cut. It is general practice to use for roughing cuts a fast feed with a comparatively slow speed, and for finishing cuts a slow feed with a comparatively high speed in order to acquire the desired smoothness of surface.

Upon the calculator might appear such a statement as:—"This calculator applies for jobs with high-speed steel cutters and average finish in one cut. Where two cuts are necessary, use twice the estimated feed for the roughing cut, and halve the estimated feed for finishing cut. For Sawing operations always use one-half of the estimated feed." Let us first consider the use of the calculator for the average one-cut job. With a given feed there always goes a given speed for each kind of material, and if the feed increases the speed also increases. Considering now the roughing cut in a two-cut operation, we use twice the estimated feed, but do not increase the speed of the cutting tool, thus insuring a high feed with a comparatively low speed as intended. Considering now the finishing cut in a two-cut operation, we use one-half of the indicated feed with the directly indicated speed, thus insuring a low feed with a comparatively high speed as indicated.

Obviously, the number, kind, arrangement and substance of the tables used may be revised in order to adapt the calculator to particular needs of various machines, operations, materials, special tools, etc. The feature of primary importance is the provision of a movable element with indicia, which when said element is progressively shifted in accordance with co-related tables indicates a result which in effect is the composite of selected portions of those tables.

Having thus described my invention, what I claim and desire to protect by Letters Patent of the United States is:—

1. A calculator, comprising an element having a longitudinally extending channel and apertures opening laterally into said channel, and a second element slidably mounted within said channel, tables carried by said first element adjacent to a plurality of said apertures, and indicia carried by said second element and visible through said apertures in relation to said tables, said second element being movable step-by-step in accordance with selective items of said tables in sequence, and a portion of said indicia being finally visible through one of said apertures and representing a composite of the items selected from said tables.

2. A calculator for the proper setting of machinery, comprising an element carrying tables of the controlling factors for such machine setting and each table having a plurality of items, and a second element carrying indicia and movable in accordance with the selected items of each of said tables in sequence, whereby the final position of said second element with respect to said first element indicates a portion of said indicia which represents the composite of the respective items selected from said tables.

3. A calculator for the proper setting of the feed of a milling machine, comprising an element having tables representing the relative strength of the article to be milled, the relative strength of the clamping device, the operation

to be performed, the width and depth of the cut, the material of the article, the power of the machine and the diameter of the cutter, and a second element slidable with respect to the first and carrying indicia which with respect to the items of said tables permits said second element to be moved step-by-step, until that portion of said indicia in final position with relation to a given portion of said first element represents the composite of the selected items of said tables, that is, the rate of feed for the machine.

4. A calculator for the proper setting of the feed of a milling machine, comprising an element having tables representing the relative strength of the article to be milled, the relative strength of the clamping device, the operation to be performed, the width and depth of the cut, the material of the article, the power of the machine and the diameter of the cutter, a second element

slidable with respect to the first and carrying indicia which with respect to the items of said tables permits said second element to be moved step-by-step, until that portion of said indicia in final position with relation to a given portion of said first element represents the composite of the selected items of said tables, that is, the rate of feed for the machine, and a separate table carried by said first element listing the materials of which the article to be milled may be composed, and a separate set of indicia carried by said second element and comparable with said last-named table, whereby that portion of said last-mentioned indicia opposite the name of the material of the particular article when said second element is in its final position indicates the cutting speed of the cutting tool for that article.
